[57] CLAIM

The ornamental design for a juvenile walker, as shown and described.

DESCRIPTION

FIG. 1 is a front elevational view of a juvenile walker showing my new design;

FIG. 2 is a top plan view thereof;

FIG. 3 is a bottom plan view thereof;

FIG. 4 is a rear elevational view thereof, the opposite side elevational view being a mirror image of that shown;

FIG. 6 is a perspective view thereof;

FIG. 7 is a perspective view thereof, with the caster wheels in retracted condition; and

FIG. 8 is a perspective thereof showing the walker in collapsed condition.

FIG. 2FIG. 1FIG. 5FIG. 4FIG. 3FIG. 6FIG. 7FIG. 8
